ROBERT HOPFELT, OF BERLIN, GERMANY.

ELECTRIC RESISTANCE APPARATUS.

SPECIFICATION forming part of Letters Patent No. 739,181, dated September 15, 1903.

Application filed January 28, 1902. Serial No. 91,604. (No model.)

To all whom it may concern:

Be it known that I, ROBERT HOPFELT, a subject of the German Emperor, residing in Berlin, in the German Empire, have invented 5 certain new and useful Improvements in Electric Resistance Apparatus, of which the following is a full, clear, and exact description.

The attempt has been made to use graphite resistances, which stand an extremely high temperature and can store up a greater amount of heat than any other kind, and when one uses graphite as a resistance material there is experienced the further advantage of having at disposal a material that is very cheap and is incombustible, so that such a resistance device is considerably more durable than the usual metallic ones. Such graphite resistances were formerly constructed like the metallic ones in that there were employed metallic contact-plates which were pushed into the graphite mass, eventually switching out the resistance by metallic contact. The mass heretofore employed consisted of flake-graphite. When the knife-contacts cut into the pulverized mass, they form a furrow or groove, which when the knife is withdrawn must be refilled with graphite, else the contact between the knives and the graphite would be imperiled. Naturally the graphite mass will by this disturbance partly fly away, and for this reason the cutting out of the resistance in the same box that contains the graphite is impossible. It is therefore necessary to provide a current-interrupter outside the box. Such resistances have in some cases proved satisfactory.

It has been discovered that pulverized graphite has the remarkable property that its resistance varies with the current. After long experimenting I have found that this quality of pulverized graphite thus used in a resistance device is exactly similar to the action of a "coherer" in a wireless-telegraphy apparatus and for convenience I will refer to this as a "coherer action." Small sparks are formed between the individual carbon particles when the coherer action takes place, so that the graphite then participates only partially in the conduction of the current, the air being the chief agent therein. The change in the resistance of such a resistance device is con-

siderable. A resistance of thirty-three ohms was in one instance reduced to only two ohms, the tensison being constant at one hundred and fifty volts. As soon as one smartly raps such a resistance apparatus the resistance is at once increased, despite the passage of the current. From this we can see that it is not the heating effect of the current but this coherer action that causes the change in the conductivity. As soon as the current is interrupted the resistance increases of itself and generally after one to five minutes resumes its original value without any shaking or other mechanical action being necessary. If instead of graphite there is used a metallic powder, the separate particles of this latter naturally melt together, and their original resisting value cannot be reattained without shaking or jarring, despite the fact that metallic powder also changes its resistance at once by reason of the passage of the current. As, however, carbon particles cannot melt together their resistance changes of its own accord after the current is cut off. As soon as the current becomes constant the change in the resistance ceases, as the coherer action is principally dependent upon the magnitude or volume of the current and hardly upon the element of time. With constant current the resistance reaches after a few seconds a constant value, but decreases or increases at once with increase or decrease of the current. The employment of such resistance-boxes as starting-rheostats for electric motors is therefore almost ideal, as all sudden changes are thereby absolutely prevented. As metallic particles are easily sublimated, I employ for contact-plates solid carbon plates. The sublimated metal would cover the carbon particles after awhile, and the resistance apparatus will, like a metallic coherer, diminish in resisting effectiveness, but will not increase again therein by shaking or jarring. It is then not advisable in the case of such resistance devices to bring the pulverized resistance mass, consisting of graphite or a similar substance, in contact with metal of any kind, for the graphite is easily brought to a glow and can under certain conditions attain such a high temperature that the conducting-plates when consisting of iron, copper, or similar metal would be melted. The

metal would be sublimated, and the so-called "coherer action" of the pulverized graphite would be prevented. To avoid this evil, the pulverized carbon mass is, according to the 5 herein-described invention, arranged between hard solid carbon plates which for practical purposes are covered on the exterior side with metal plates in order to conduct the heat away with the greatest possible rapidity. In order to prevent layers of 10 air remaining between the carbon plates and their metal coverings and which would be bad conductors, it is preferable to form the carbon plates upon the metal plates themselves. After the baking the carbon plates adhere closely to the metal. The metal plates can be provided with small projections, which hold the carbon plates, but which, however, must not project clear through the latter. 15 20 The conduction of the current takes place through the solid carbon plates practically by means of the metal plates, so that the solid carbon plates prevent the direct passage of the current between the powdered carbon mass and the metal plates.

In the accompanying drawings I have illustrated a resistance constructed as described. Figure 1 is a side elevation. Fig. 2 is a longitudinal section; and Fig. 3 is a cross-section 30 on the line 3 3, Fig. 2.

In the figures, *b* represents contact-plates in contact with the graphite mass *f*, which is confined in place between the contact-plates by the insulating rings or frames *a*, held between the plates *b*. Any suitable number of 35

these plates, rings, and graphite masses may be fitted together and held by any suitable means, as by clamping-plates *c* and bolts *d*. These plates *b* are preferably of metal faced with carbon *e*, as shown, in order to conduct 40 the heat from the resistance to the outside air and to prevent the metal from coming into direct contact with the graphite, and so becoming sublimated. The electrical connections are to the several plates *b*, so that 45 the current entering through any such plate will flow through the graphite mass, then through the next contact-plate, and so on.

I claim as my invention—

1. An electric resistance device having 50 frames, in combination with contact-plates arranged between the frames and covering both sides of the same, a pulverized resistance mass closely surrounded by said frames and plates, to give coherer action on a passage of 55 current, substantially as described.

2. An electric resistance device having metal plates with carbon facings in combination with a resistance mass of pulverized carbon material confined between and in contact with the carbon facings of the plates and adapted to give coherer action on a passage of 60 current, substantially as described.

In testimony whereof I have signed my name to this specification in the presence of 65 two subscribing witnesses.

ROBERT HOPFELT.
